(75) Inventor: **Leonora M. Brozell**, Toledo, OH (US)

Primary Examiner—Cathron Brooks

(73) Assignee: **Owens-Illinois Closure Inc.**, Toledo, OH (US)

(57) **CLAIM**

(**) Term: **14 Years**

The ornamental design for an actuator and cowl for a lotion dispensing pump, as shown and described.

(21) Appl. No.: **29/111,866**

DESCRIPTION

(22) Filed: **Oct. 5, 1999**

FIG. 1 is a perspective view showing my new design;

(51) LOC (7) Cl. **09-07**

FIG. 2 is a reduced left side elevational view showing a

(52) U.S. Cl. **D9/448**

container in broken lines;

(58) Field of Search D9/300, 434, 447,

FIG. 3 is a top plan view;

D9/448; 222/320, 321.1, 321.6, 321.7, 321.8,

FIG. 4 is a front elevational view;

321.9

FIG. 5 is a left side elevational view;

FIG. 6 is a rear elevational view;

FIG. 7 is a perspective view of a modified embodiment; and,

FIG. 8 is a left side elevational view of the modified

embodiment.

The right side elevational view of each embodiment is a mirror image of the left side elevational view. The top view of the modified embodiment is the same as the corresponding view of the first embodiment.

The broken line showing of a container is for illustrative purposes only and forms no part of the claimed design.
